[54] PIEZOELECTRIC IGNITION MECHANISM
13 Claims, 9 Drawing Figs.

[52] U.S. Cl..... 431/255,
310/8,7

ABSTRACT: A piezoelectric ignition mechanism which produces a series of voltage surges so as to create a series of sparks across spaced terminals rather than a single spark upon impacting a piezoelectric crystal. This result is attained by using a buffer which causes the crystal to reverberate.

PIEZOELECTRIC IGNITION MECHANISM

BACKGROUND OF THE INVENTION

It is a well-known phenomenon that certain crystals such as quartz and some ceramics have the property of producing a potential difference across the faces of the crystal when the latter is stressed. It is also known that a higher voltage can be produced by applying an impact force rather than a steady compressive force to the crystal.

By applying an impact force to a crystal, a spark can be made to jump a gap between two electrodes which are connected across the faces of the crystal by leads. Thus, one electrode is at a negative and the other electrode is at a positive potential. This effect has been used in a number of articles such as a cigarette lighter or internal combustion engine for example. A gas, such as butane, is timed to pass between the electrodes when the piezoelectric crystal is struck. When the spark jumps the gap between the electrodes it ignites the butane gas, and the issuing flame can be used to light a cigarette or fire a combustible mixture in a gas cylinder. In the prior art, only one spark jumped the gap, therefore, if the gas did not ignite on the first attempt, the operation had to be repeated. It has been shown that it takes time for the crystal to recover in order to produce a second voltage across the electrodes which is equal to the first. If one continues to strike the crystal each subsequent impact products a lower voltage and a proportionately less chance of igniting the gas.

SUMMARY OF THE INVENTION

This invention has greatly improved the prior art piezoelectric devices by utilizing an impact mechanism which permits a series of sparks to be produced across the electrode gap with only one impact. The series of sparks greatly increases the chances of successfully igniting the gas issuing between the electrodes.

In the improved arrangement of this invention, the piezoelectric crystal is supported in a mounting which is so constructed and proportioned that it will reverberate when the crystal is struck. The crystal is struck in such a manner that the timing of the reverberations in the mounting will be related to those in the crystal so as to induce a series of strong voltage oscillations whereby to extend the time during which current flows between the electrodes forming a spark gap; thereby, providing more reliable ignition, because the probability that ignition will occur has been increased.

BRIEF DESCRIPTION OF THE DRAWINGS

For a better understanding of the present invention, reference may be had to the accompanying drawings in which:

FIG. 1 is a side view showing parts in section;

FIG. 2 is an end view showing parts in section;

FIG. 3 is a side view showing the details of the cartridge impact mechanism;

FIG. 4 is an end view showing the details of the cartridge impact mechanism;

FIG. 4a is a detail showing the buffer mechanism;

FIG. 5 is a side view with a portion cut away showing the impact mechanism in actuated condition;

FIG. 6 is an end view with parts cut away showing the impact mechanism in actuated condition;

FIG. 7 is a modification of the device shown in FIG. 1; and

FIG. 8 is a perspective of an end plate.

DESCRIPTION OF THE PREFERRED EMBODIMENT

Referring to FIG. 1 there is depicted a flame-producing mechanism in the form of a cigarette lighter. The invention disclosed herein is adapted to be used with any mechanism for producing a spark.

The lighter shown comprises a sheath 11 which fits over and retains in operative position the working components of the lighter. A fuel reservoir 12 is mounted within the confines of the sheath 11. The walls forming the fuel reservoir can be

shaped so as to fit within the sheath 11 and still leave space available for other elements. A socket 13 is formed in the top wall of the fuel reservoir 12 into which there is received a known burner valve such as disclosed in U.S. Pat. No. 2,571,435 which issued on Oct. 16, 1951. A socket 14 is fixed to the lower wall of the fuel reservoir 12 and extends into the fuel reservoir. An inlet valve 15 which permits fuel, such as a liquefied butane, to be injected into the fuel reservoir is mounted within the socket 14. The inlet valve can be any known inlet valve, for example, the valve shown in U.S. Pat. No. 3,085,601 which issued on Apr. 16, 1963. A flange 16 having upstanding walls 17 thereon is formed outwardly of the fuel reservoir 12 to form a receiving means for structure to be fully disclosed hereinafter.

10 15 A fingerpiece 18 is attached to a support 19 having depending legs 20 thereon. The depending legs 20 are axially aligned above a lever 21 which has one end fixed to the movable stem 13a on the burner valve. The lever has a finger 22 thereon which functions as a fulcrum in which the finger 22 rests on the top wall of the fuel reservoir 12. The burner valve is of the type having a movable stem 13a although any other suitable valve can be used. When the stem 13a is raised the valve is opened and gas flows. The stem 13a is held in closed position by a spring (not shown) mounted within the valve housing. To open the burner valve and thereby permit gas to flow, the fingerpiece 18 is depressed and the depending leg 20 contacts the end of the lever 21 which is rotated about the fulcrum 22. Since the end of the lever is attached to the stem 13a of the 20 25 30 burner valve, the stem is lifted and fuel contained in the reservoir 12 can flow to the atmosphere.

The fingerpiece 18 also functions to actuate the ignition mechanism 23. This is accomplished by fixing a housing 24 to the fingerpiece 18. The housing is preferably tubular in construction, however, any desired shape can be used. The housing 24 has a coiled spring 25 attached therein which can be compressed within the housing 24. The support 19 has notches 19a formed therein for the reception of a pair of opposed struts 26 which can be in the form of U-shaped wire members. The struts 26 are flexible parallel members and each set is biased inwardly towards the other set. The struts are firmly held in place by being clamped between the fingerpiece 18 and the support 19 as shown in FIG. 4.

35 40 45 A tubular housing 27 having opposed ends 28 and 29 which are peened over is loosely received within the walls 17 and rests on the flange 16. The housing 27 contains a piezoelectric crystal firmly held in a housing 30. The crystal is encapsulated in a cartridge having an anvil 31 protruding therefrom. Connected to the opposed faces of the crystal is a lead wire 32 which terminates in an electrode 33 mounted in an insulated member 33a which can be a ceramic or a plastic for example. The anvil 31 extends through an opening in the crystal housing 30. The anvil 31 which abuts the encapsulated crystal extends downwardly beyond the confines of the encapsulated crystal housing 30. The anvil 31 is preferably made of metal which enables it to withstand the impact imparted to it by a hammer 35. The hammer 35 is also preferably metallic and of relatively high density. The hammer 35 is slidably received within the 50 55 60 65 70 75 80 85 90 95 99 100 housing 27. The hammer can be seen through an opening 36 in the housing 27. A boss 37 having a flange 38 thereon is fixed to the lower portion of the housing 27. A coiled spring 39 fits around the boss 37 and bears on the flange 38 integral with the boss 37. A bore 40 is countersunk in the hammer 35 and receives the opposite end of the coiled spring 39. Thus, the hammer 35 is maintained firmly against the anvil 31 by the bias of the spring 39. A notch 41 is formed in the hammer 35 adjacent the upper portion thereof. The bight 26a of the U-shaped strut 26 fits within a corresponding opposed notch 41 in the hammer 35. The cutout portion 36 of the housing 27 gradually tapers outwardly and forms a cam surface 42. When the fingerpiece 18 is depressed, the struts 26 which are located in recesses 41 move the hammer 35 downwardly against the bias of the spring 39. The struts 26 are cammed out of the notches 41 by the cam surface 42 after the hammer 35 has

travelled approximately three-eighths to one-half inch. When the struts are removed from the notches, the hammer is accelerated into an impact engagement with the anvil 31. Upon release of the fingerpiece 18, the spring 25 returns the fingerpiece with the struts 26 affixed thereto to its rest position. The bight 26a on each of the struts thereby reengages in its respective notch 41 because the struts are flexibly urged inwardly towards each other.

A series of elements which can be metallic and can be in the form of washers 56 or solid wafers 57 or a solid member 55 is placed above the crystal housing 30. A combination of washers and wafers can also be used. A solid end plate 55 can be also used either alone or in combination with washers and/or wafers over which the end of the housing 27 is peened. The effect of placing a solid plate or washers and/or wafers adjacent the encapsulated crystal 30 is to create a series of sparks which increases the probability of an ignition occurring.

In the normal arrangement where the crystal is energized by impact, the action of striking the crystal produces only one positive and one negative voltage surge at the live electrode of very brief duration. The brevity of the resulting discharge frequently fails to cause ignition. The number of washers and/or wafers or the thickness of the solid member is chosen so that the reverberations in the crystal and the washer-wafer assembly resulting from the impact of the hammer 35 interact to produce three or four voltage peaks occurring in about 100 microseconds from the first impact.

In another embodiment of the invention, the encapsulated crystal in its housing 30 is held by a block 47. The block can be received within a cigarette lighter housing or in any other environment generally shown by dashed lines in FIG. 7. The block 47 has an opening 48 therein which is dimensioned to receive the crystal housing 30. The lead wire 32 from the crystal can be snaked through a bore in the block and then it terminates in an electrode 33. The electrode extends through an insulating member 49 which can be made of any known insulating material.

A solid end plate 50 which is preferably metallic—however, any material can be used—is forced into the upper portion of the opening 48 so as to exert a compressive force against the crystal assembly. The plate 50 can be given a slight chamfer along one side to provide a lead-in and the slot in the block 47 is dimensioned so that the plate 50 is a forced fit therein. Thus, when the crystal assembly and plate are locked in position by forcing the plate into the opening 48, the crystal is subjected to a compressive force.

A very satisfactory output has been made in practice by making the plate 50 and block from brass with a wall thickness not less than 0.08 inch.

The end plate 50 can be formed with a pair of outward extensions 51 so that better reverberation characteristics can be imparted to the crystal from the end plate 50 which is shaped like a bridge.

A hammer 52 having a head 53 thereon is pivoted by means of a pin 54 to the block 47. Any known mechanism can be used to place the hammer under tension and then release the latter to strike the crystal as detailed in the first embodiment of this invention.

It is possible that, instead of using a separate solid member or washers or wafers, the end of the crystal unit could bear against a fingerlike portion formed integrally with the housing and dimensioned to have the required reverberation characteristics.

The flame which is produced can be adjusted by a knob 43 which, by means of a bushing 44, is connected such as by splines to the burner valve. Since the burner valve is not part of this invention further detail is considered to be superfluous. A closure 45, having an opening 46 therein for the inlet valve 15, closes the lower portion of the lighter and retains the elements therein.

To operate the ignition mechanism, the fingerpiece 18 is depressed, and since the struts 26 are connected to the finger-

piece, they are moved downwardly also. The struts, which are resiliently biased inwardly towards each other have a bight portion 26a which fit within a respective notch 41. As the fingerpiece 18 is depressed, energy is stored in the spring 39 and when the struts 26a reach the cam portion 42 of the housing 27 they are biased outwardly away from each other thereby removing them from the notches. The downward movement of the fingerpiece 18 also causes the leg 20 to tilt the lever 21 about its fulcrum 22 and thereby open the valve 13a to cause gas to flow past the electrode 33.

When the hammer 35 is suddenly released by removing the restraint of the struts 26a, the energy stored in the spring 39 will force the hammer to strike the anvil 31. Since the anvil is in contact with the piezoelectric crystal, a potential difference appears across the faces of the crystals. The electrode 33 is connected to one face of the crystal and the other electrode is grounded. Since the burner valve 13a is at ground potential, it forms the other electrode and a series of sparks will jump the gap between the electrode 33 and the burner valve 13a to thereby ignite the gas emanating from the burner valve.

Although the exact mode of operation of the ignition device is not fully understood, it is believed that the operation may be described as follows: the action of striking one end of the crystal produces a shock wave which travels through the crystal and causes the plate 50 to be deflected away from the other end of the crystal. The crystal also contracts to produce, for example, a positive-going voltage peak at the live electrode 33. The crystal then expands to produce a negative-going voltage peak, after this the plate 50, reverting to its normal position, strikes the adjacent end of the crystal which again contracts to produce a positive-going voltage peak and then expands to produce a negative-going voltage peak. The reverberations in the crystal and plate may continue but subsequent voltage peaks may not have sufficient amplitude to produce a discharge.

The energy available at the spark gap is increased considerably in the ignition units according to the present invention. In mechanisms of the prior art only the energy of the initial two voltage peaks is usually available as energy for ignition at the spark gap whereas in the arrangement of the present invention, the first four peaks at least are each effective to produce a discharge.

We claim:

1. A mechanism for creating an electrical discharge comprising:
  - a. a piezoelectric crystal mounted on a support,
  - b. an impact means for striking said piezoelectric crystal mounted adjacent said crystal so as to induce a primary voltage,
  - c. electrical leads connected to said crystal and terminating in a pair of electrodes forming a spark gap,
  - d. a buffer means mounted adjacent said crystal to induce secondary vibrations of said crystal whereby said crystal will produce secondary electrical discharges subsequent to being struck by said impact means and upon reaction with said buffer means.
2. A mechanism for creating an electrical discharge as defined in claim 1 further characterized in that said buffer comprises at least one disc-shaped member.
3. A mechanism for creating an electrical discharge as defined in claim 2 further characterized in that said disc-shaped member has an opening therein.
4. A mechanism for creating an electrical discharge as defined in claim 1 further characterized in that said buffer comprises a relatively thick, solid end plate.
5. A mechanism for creating an electrical discharge as defined in claim 4 further characterized in that said end plate has extensions on opposite ends thereof forming a bridge shape.
6. A mechanism for creating an electrical discharge as defined in claim 1 further characterized in that said impact means comprises a hammer which is urged against piezoelectric crystal by a spring.

7. A mechanism for creating an electrical discharge as defined in claim 1 further characterized by a first housing enclosing said piezoelectric crystal and said impact means are in axial alignment and are firmly held within said first housing.

8. A mechanism for creating an electrical discharge as defined in claim 7 further characterized in that said buffer is mounted within said first housing between said crystal and the top portion of the first housing.

9. A mechanism for creating an electrical discharge as defined in claim 7 further characterized in that a second housing is telescopically received over said first housing, in which a fingerpiece is fixed to said second housing, means on said fingerpiece which engages said hammer and depresses it against the bias of the spring and releases said hammer after a predetermined amount of energy is stored in said spring.

10. A mechanism for creating an electrical discharge as defined in claim 1 further characterized in that said first housing is a block having an opening therein for the reception of said crystal.

11. A mechanism for creating an electrical discharge as defined in claim 10 further characterized in that said hammer is pivotally attached to said block and the hammerhead is in axial alignment with said crystal so as to strike the latter.

12. A mechanism for creating an electrical discharge as defined in claim 1 further characterized in that a fuel reservoir is adjacent said crystal, said fuel reservoir has a burner valve mounted on one end thereof, a fingerpiece mounted on said support to actuate the burner valve and the impact means, an electrode mounted adjacent said burner valve and electrically connected to said crystal such that upon actuation of said impact means, a spark ignites the gas emanating from said burner valve.

13. A mechanism for creating an electrical discharge as defined in claim 1 further characterized by a fuel reservoir mounted adjacent said crystal and having a flange thereon upon which said crystal is received.
